(57) **CLAIM**

The ornamental design for a display screen with a transitional graphical user interface for an emergency resource assignment software, as shown and described.

DESCRIPTION

FIG. 1 is a front view of a first image of a display screen with a transitional graphical user interface for an emergency resource assignment software;

FIG. 2 is a front view of a second image thereof;

FIG. 3 is a front view of a third image thereof, comprising solidly shaded areas that are part of the claimed design;

FIG. 4 is a front view of a fourth image thereof;

FIG. 5 is a front view of a fifth image thereof, comprising solidly shaded areas that are part of the claimed design; and,

FIG. 6 is a front view of a sixth image thereof, comprising solidly shaded areas that are part of the claimed design.

The broken lines in the drawings depict portions of the display screen that form no part of the claimed design.

The appearance of the transitional image sequentially transitions between the images shown in FIGS. 1-6. The process

or period in which one image transitions to another image forms no part of the claimed design.
